KNITTING MACHINE

Vaughn H. Butler, Harriman, Tenn., assignor, by mesne assignments, to Scott & Williams, Inc., Laconia, N.H., a corporation of Massachusetts

Filed June 22, 1956, Ser. No. 593,228

4 Claims. (Cl. 66—57)

This invention relates to circular knitting machines, and in particular to an improved two-feed knitting machine, to novel methods involved in its operation, and to an improved stocking resulting therefrom.

The principal object of the invention is to provide an improved two-feed knitting machine of outstanding versatility, adapted to knit single feed or double feed, and to knit plain or mesh patterns in either stretch or non-stretch stockings. A related object is to provide a high production knitting machine of simple and durable construction, and superior operation.

Another object of the invention is to provide a two-feed knitting machine adapted to be constructed by minimum modification of standard and widely used existing single feed machines, such as Scott and Williams Models K and KN.

A further object is to provide simple and effective eyelet closing means, utilizing needle cams to divide the needles for such purpose. A related object is the provision of an auxiliary cam assembly including a stitch cam having a unique sloped step therein. Another related object is the provision of a novel delayed action yarn shear actuating device.

Still another object is the provision in a circular knitting machine of a space-saving cam assembly, which includes gusset raising and lowering cams and a clear cam.

Another object is the provision of a novel two-feed knitting method, wherein tuck stitches are knitted at one feed and plain stitches at another, to effect a distinctive mesh pattern in the resultant product.

Still another object is the provision of a unique method of closing eyelets in two-feed knitting wherein an auxiliary yarn is inserted into and withdrawn from the body of a tubular article.

Yet another object is the provision of a novel, seamless stocking, the body of which is knit in a distinctive mesh pattern which is preserved across the instep. The stocking may be provided with a similar but contrasting pattern in the shadow welt.

Another object is the provision of a seamless stocking composed of two body yarns knitted in rotation, one of the body yarns being inserted into and withdrawn from the body of the stocking, wherein the eyelets at the points of yarn insertion and withdrawal are effectively closed by yarn ends knitted into the fabric.

Further objects will be in part evident and in part pointed out hereinafter.

The invention and the novel features thereof may best be made clear by reference to the following description and the accompanying drawings in which:

FIGURE 1 is a side elevational view of an exemplary circular knitting machine constructed in accordance with the invention;

FIGURE 2 is a top plan view, partly in section, of the machine of FIGURE 1, taken on the line 2—2 thereof;

FIGURE 3 is a plan view corresponding to FIGURE 2, with the latch ring of the machine and associated elements pivoted out of the way, and with the dial removed;

FIGURE 4 is a linear development of the cams utilized in knitting;

FIGURE 5 is a front elevational view of the cam

assembly including the gusset raising and lowering cams and a clear cam;

FIGURES 6 and 7 are top plan views of the assembly of FIGURE 5, in different operating positions;

FIGURE 8 is a front elevational view of the auxiliary stitch cam assembly;

FIGURE 9 is a rear elevational view of the auxiliary cam assembly of FIGURE 8;

FIGURE 10 is a sectional view through the cam assembly of FIGURE 8, taken on the line 10—10 thereof;

FIGURE 11 is a top plan view of the auxiliary cam assembly of FIGURE 8, shown in operative relationship with the needle cylinder and means for actuating the cam assembly;

FIGURE 12 is an elevational view, partly sectioned, of the auxiliary cam assembly of FIGURE 8, illustrating its operative relationship to the sinker cap of the machine and the auxiliary sinker cam incorporated therein;

FIGURE 13 is a fragmentary top plan view of the sinker cap and the auxiliary sinker cam;

FIGURE 14 is a fragmentary bottom plan view of the sinker cap showing details of the auxiliary sinker cam and its backing cam;

FIGURE 15 is a top plan view of the dial cap of the machine, showing the yarn clamps and shears;

FIGURE 16 is a side elevational view of the dial cap of FIGURE 15, viewed from the bottom thereof;

FIGURE 17 is a side elevational view of the dial drive;

FIGURE 18 is an elevational sectional view through the dial drive taken substantially on the line 18—18 of FIGURE 17;

FIGURE 19 is a top plan view of the latch ring of the machine, showing the auxiliary yarn fingers and actuating mechanism therefor;

FIGURE 20 is an elevational view of the latch ring of FIGURE 19, taken on the line 20—20 thereof, showing the opening for the auxiliary yarn fingers;

FIGURE 21 is a sectional elevational view taken on the line 21—21 of FIGURE 19;

FIGURE 22 is a diagrammatic view illustrating the needle arrangement in the cylinder of the machine;

FIGURE 23 is an enlarged fragmentary view illustrating the positional relationship of the needles to an auxiliary yarn finger;

FIGURE 24 is a diagrammatic illustration of the auxiliary racking mechanisms;

FIGURES 25 and 26 are sequential illustrations of needle separation and actuation at the auxiliary knitting station, utilized in eyelet closing on insertion of an auxiliary body yarn;

FIGURE 27 shows a preferred type of stocking produced by the machine and method of the present invention;

FIGURE 28 illustrates the mesh pattern of the body of the stocking of FIGURE 27;

FIGURES 29, 30, and 31 are fragmentary illustrations of a pattern layout chart suitable for production of the stocking of FIGURES 27 and 28, FIGURE 29 representing the layout of the fabric, FIGURE 30 representing the arrangement of the selector drum jacks, and FIGURE 31 the arrangement of the cylinder jacks; and

FIGURES 32 and 33 are respectively illustrations of the fabric where the auxiliary yarn is removed and inserted.

In the drawings, the invention is illustrated as incorporated in the well-known Scott & Williams 400 needle Model KN machine. The upper part of the machine, as shown in FIGURE 1, includes the conventional lower bed plate 1, upper bed plate 2, side standard 3, cylinder 4, sinker cap 5, latch ring 6 and the dial drive pinion 7.

Mounted on the lower bed plate 1 is the usual selector drum 8. The knitting station of the machine is unchanged, and is designated in the drawings as main knitting station M. The principal modification of the machine involves the addition of an auxiliary knitting station designated as A.

For this purpose, the gusset raising and lowering cams and the clear cam of the machine are removed from the upper bed plate, and replaced by a unitary cam assembly including all three cams, at the position of the replaced clear cam. This assembly, indicated generally as 10 in FIGURE 4, is illustrated in detail in FIGURES 5, 6 and 7. As there shown, the cam assembly includes a base block 11 having bars 12 and 13 slidably mounted therein. At its inner end, slide bar 12 supports the lowering cam 14, and at its outer end the slide bar carries an adjustable stop 15 cooperative with the base block 11 to adjustably limit the forward movement of the lowering cam. Slide bar 13 carries the raising cam 16 on its inner end, and its outer end is also provided with an adjustable stop 17.

A lever 20 is pivotally mounted atop the base block 11, and engaged by rigid links 21 to posts 22 and 23 extending upwardly, respectively, from the slide bars 12 and 13, whereby rotation of the lever 20 may effect differential movement of cams 14 and 16, by simultaneously advancing one slide bar and retracting the other. In FIGURE 6, the raising cam 16 is advanced to operative position, whereas in FIGURE 7 the lowering cam 14 is similarly advanced. The lever 20 may be normally disposed at a position intermediate the positions of FIGURES 6 and 7 to dispose both gusset cams in inoperative position with respect to the needle butts, as will be readily understood. The gusset cams are actuated by a rod 24, extending from the arm 25 of lever 20 to the main drum actuated bell crank lever customarily employed for such purpose.

Between bars 12 and 13, the base block 11 of the cam assembly 10 carries and guides a slide bar 26, the inner end of which mounts clear cam 27. As best shown in FIGURE 5, the clear cam 27 is disposed immediately below the raising cam 16. The outer end of slide bar 26 carries an adjustable stop 28 and a downwardly extending post 29, which is engaged by a tension spring 30 to a screw 31 mounted in the bottom of the base block, whereby the slide bar 26 and clear cam 27 are biased inwardly at all times. An arm of the bell crank 33 (FIGURES 2 and 3), pivotally mounted at 34 on the upper bed plate 2 of the machine, engages the inner side of post 29, and the other arm of bell crank 33 is engaged by rod 35 to the drum actuated bell crank lever customarily utilized for clear cam actuation. The clear cam is also engaged in conventional manner to the fashion mark mechanism 36.

The space freed by consolidation of the gusset cams and clear cam into the unitary cam assembly described above is utilized as the auxiliary knitting station A. In modifying the machine to incorporate the auxiliary knitting station, see FIGURE 4, the left hand riser cam or side cam 37 is altered by cutting off the trailing end thereof. A slot 40 (FIGURE 4) is cut in the cam ring 41 to the left of the modified side cam 37, and an auxiliary side cam 42 is mounted at the left of the slot 40. The trailing surface 43 of the auxiliary side cam 42 is inclined to raise a group of needle butts on the first reverse stroke of toe knitting. In the slot 40 is mounted the auxiliary stitch cam assembly 44, which constitutes a principal feature of the invention.

The stitch cam assembly 44 is illustrated in detail in FIGURES 8, 9, 10 and 11, and comprises a base plate 45 having guides 46 adapted to retain a T section of the slide 47 slidably mounted therebetween. A block 49 is mounted on the side of the slide 47, the block 49 having a downwardly depending tail 50 (FIGURE 9). The inner or front end of slide 47 is provided with an upwardly extending generally arcuate lug 51, on which are

mounted a clear cam 52 and center cam 53. A slot 54 in lug 51 carries a vertically slidable block 55 (FIGURE 10), on which is mounted auxiliary stitch cam 56 and a cooperative landing cam 57. A bracket 58 secured to the rear side of block 55 has a tail 59 overhanging the slide 47, and an adjustment screw 60 extends through the tail 59 into the slide. A spring 61 compressed between the slide and tail 59 urges the bracket 58 upwardly against the screw head. In this manner the block 55 is vertically adjustable with respect to the slide 47, whereby the auxiliary stitch cam 56 and its landing cam 57 may be adjusted vertically with respect to the clear cam 52 and center cam 53 of the assembly.

As an outstanding feature of the invention, the face of the auxiliary stitch cam 56 is provided with a step 63 extending thereacross, whereby the lower portion 64 thereof is recessed with respect to the upper portion 65, for a purpose presently apparent. The lower cam portion 64 is recessed preferably about .030 inch with respect to the upper cam portion. The step 63 may be horizontal, but preferably is inclined slightly downwardly from its leading to its trailing end, or from right to left as viewed in FIGURE 8.

A tension spring 66 (FIGURE 11) extends from the slide 47 of the auxiliary stitch cam assembly to a fixed part of the machine, urging the slide and its cams rearwardly and away from the needle cylinder at all times. Adjacent the cam assembly 44, a bell crank 67 is pivotally mounted at 68 on the upper bed plate 2, the bell crank having a short arm terminating in a rounded end 69 disposed adjacent the tail 50 of the slide block 49, whereby the bell crank arm may move the slide 47 and the cams carried thereby forwardly toward the cylinder 4, extending spring 66. The other end of the bell crank 67 is engaged by a rod 70 (FIGURE 12) to the main drum actuated bell crank lever 71 illustrated in FIGURE 24. The lever 71 comprises also the cam following end 72, and is pivoted at 73.

The sinker cap 5 is modified at the auxiliary knitting station as illustrated in FIGURES 12, 13 and 14. Initially, an opening 75 is cut through the top of the sinker cap at the appropriate location, and a recess 76 is milled out of the underside thereof. As best shown in FIGURE 14, an outside sinker cam 77 is suitably mounted in the recess 76. A pullout bracket 78 is pivotally mounted on the sinker cap, as by means of pin 79, the bracket carrying on its inner end an auxiliary sinker cam 80. A spring 81 extending from the bracket arm 82 to the sinker cap tends to maintain the auxiliary sinker cam in raised or withdrawn position. A downwardly and outwardly extending bracket 83 is fixedly mounted on the sinker cap below the pullout bracket 78 (FIGURE 12), and a rocker arm 84 is pivotally mounted on the bracket 83. The auxiliary stitch cam assembly slide 47 carries an upstanding lug 85 adapted to bear on one end of the rocker arm 84, as shown in FIGURE 12, and the opposite end of the rocker arm is adapted to engage arm 82 of the pullout bracket 78, whereby inward movement of the auxiliary stitch cam assembly against the cylinder effects corresponding movement of the auxiliary sinker cam 80 to operative position. Spring 81 serves to maintain the rocker arm 84 in engagement with the pullout bracket arm 82 and the slide lug 85 at all times, and to return the sinker cam 80 to inoperative withdrawn position when the auxiliary stitch cam assembly is withdrawn. As will be evident, actuation of the auxiliary stitch cam assembly effects coordinated actuation of the auxiliary sinker cam 80.

The dial cap 90 of the machine is modified as illustrated in FIGURES 15 and 16. The original clamp 91 and shear 92, and their operating rod 93, are unchanged, and utilized for clamping and shearing the main station yarn. For the auxiliary yarn, a yarn separating guide plate 94 is added to the cap, plus guide 95, clamp 96 and shear 97. The clamp 96 and shear 97 are operated by

a rod 98 extending to one end of a bell crank 99 (FIGURE 18) which is pivotally mounted at 100.

The opposite end of the bell crank 99 is engaged by a thrust rod 101. Adjacent its end engaged to rod 98, see FIGURES 17 and 18, the bell crank 99 is guided by guide 102, and carries a pivotally engaged latch 104 which extends upwardly and is biased by spring 105 toward the bearing bracket 106 of the machine. The latch 104 is provided with a step 107 adjoined by a cam surface 108, the latter being disposed for engagement by a trip cam 109 fixed on the horizontal dial drive shaft 110 of the machine. The dial cap is also provided with an upstanding bracket 111, by which it is mounted on the latch ring 6 of the machine.

The modification of the latch ring 6 is illustrated in FIGURES 19, 20 and 21. At the auxiliary station A, a yoke 115 is added to the latch ring, enclosing a longitudinal slot 116 which is extended through the latch ring and its liner 117. The edges of the liner adjoining the slot 116 are formed into inclined guides or cam surfaces 118, adapted to deflect any needle latches which might otherwise enter the slot and be damaged. Two auxiliary yarn fingers 120 are mounted in the yoke slot 116. Preferably, each auxiliary yarn finger is pivotally mounted on a pin 121, which is eccentrically mounted on and extends inwardly from a pin 122 of larger diameter, the latter pin being journaled in the yoke and secured against rotation as by a set screw 123. As will be evident, each pin 122 may be released by backing off its associated set screw 123, and rotated to adjust the pivot point of the associated yarn finger in radial direction with respect to the needle cylinder.

A bracket 125 is mounted on the left hand pivotal lug 126 of the latch ring (FIGURE 19), and a post 127 extending outwardly therefrom pivotally mounts the individual yarn finger controls 128. The outer end of each yarn finger control is linked by a link 130 to one of the auxiliary yarn fingers 120, the link engaging approximately the center of the latter, and midway of its length each finger control 128 is provided with a laterally extending element 131 cooperative with a thrust bar 132. A downwardly extending spring 134 maintains each control in lowered position, except when elevated by the associated thrust bar. Obviously, more than two auxiliary yarn fingers may be provided if desired.

The arrangement of the needles in the cylinder of the machine, according to the lengths of their butts, is illustrated in FIGURE 22, wherein the arrow 140 indicates the direction of cylinder rotation in round and round knitting. The needles include the short butt group H, utilized in heel knitting, which by way of example may comprise 156 needles having .240 inch butts. The short butt needle group H is adjoined on either side by needle groups 141 and 142, each of these groups comprising 20 .300 inch butt needles. The long butt needles T utilized for toe knitting include group 143, comprising 9 .338 inch butt needles, group 144 comprising 45 .390 inch butt needles, group 145 comprising 97 .338 butt needles, group 146 comprising 44 .390 inch butt needles and group 147 comprising 9 .338 inch butt needles. The needle arrangement thus far described is entirely conventional. In accordance with the present invention, however, a number of the leading short butt needles are replaced by needles having butts of length intermediate that of the other short butt needles and the adjoining .300 butt needles. By way of example, and as illustrated in FIGURE 22, the leading short butt needles 148, 17 in number, may have .270 inch butts. These needles are employed in closing eyelets on withdrawal of an auxiliary yarn at the auxiliary station, as will hereinafter appear. Near the trailing end of the short butt group, several needles 149 are also provided with butts of intermediate length, such as .270. The needles 149, which may be six in number, are preferably alternated with other short butt needles as shown, and are spaced from the end of the short butt group by a few

.240 butt needles 150, which may be six in number. The needles 149 are utilized in eyelet closing on insertion of an auxiliary yarn at the auxiliary station, as will be described in detail hereinafter. As shown in FIGURE 23, each auxiliary yarn finger 120 is adjusted inwardly to approach very closely, when introduced, cleared needles passing thereby, so that the exemplary cleared needle 151 brushes closely by the yarn finger.

Referring to FIGURE 24, the high speed gear 155 of the machine is provided with a suitably positioned stepped cam 156, which replaces the standard cam normally provided to take the machine out of the heel and toe. The stepped cam 156 is adapted to engage the cam follower 157 of the auxiliary clutch pawl 158. The belt shipper drum 160 is provided with a suitably positioned notch 161, and the main pattern drum 162 of the machine is provided with similarly stepped cams 163 and 164, which are utilized for stepwise insertion and withdrawal of the auxiliary stitch cam assembly.

The machine modified as above described is adapted to knit a novel and improved stocking 170, illustrated in FIGURE 27, the stocking including welt 171, shadow welt 172, leg 173, heel 174, foot 175 and toe 176. The body of the stocking, including the leg 173 and foot 175, are knitted in the distinctive mesh pattern illustrated in FIGURE 28, wherein alternate courses 177 include spaced held loops 178 at regular intervals, and intervening courses 179 are composed of plain knit stitches except where the held loops are cast off to form tucks. The body mesh pattern is illustrated also in FIGURE 29, the darkened squares 178 representing held loops. It will be noted that the held loops in successive courses 177 are offset according to an irregular pattern, whereby the formation of perceptible pattern lines in the stocking fabric is avoided.

For knitting the mesh pattern of FIGURES 28 and 29, the selector drum pattern jacks may be in accordance with FIGURE 30, the darkened squares 182 therein representing butts removed. The corresponding cylinder 40 jack butt arrangement is indicated in FIGURE 31, wherein the darkened squares 184 represent nibs or butts remaining on the cylinder jacks. The pattern of rows I through P in FIGURE 31 extends preferably through 160 needle jacks, the illustrated pattern of rows R through Y 45 extending through the remaining 240 needle jacks.

Operation

The operation of the machine and the novel knitting methods involved will be described in connection with knitting of the exemplary stocking 170 of FIGURE 27. In this particular example, only a single auxiliary yarn finger 120 is utilized at the auxiliary knitting station. The knitting cycle begins in conventional manner with bare needles, knitting being initiated at the main station only. For make-up, the first four courses of knitting, two yarns may be employed, for example a 50 denier multi-filament nylon welt yarn and a 50 denier multi-filament nylon heel and toe yarn. After completion of the make-up, the heel and toe yarn is withdrawn by a drum movement, and plain knitting proceeds with the welt yarn. The same drum movement which withdraws the heel and toe yarn is utilized to move the clear cam 27 of the cam assembly 10 into operative position against the cylinder. This is accomplished in conventional manner by displacing rod 35 and the associated bell crank 33, see FIGURES 2 and 5, whereby the bell crank acting in conjunction with post 29 permits displacement of slide bar 26 under the influence of its spring 30, thereby moving the clear cam 27 in against the needle butts. Plain knitting of the welt at the main station M then continues.

Throughout the make-up and welt knitting, the auxiliary stitch cam assembly 44 and the auxiliary sinker cam 80 are in inactive or withdrawn position. The patterning mechanism, employing two selector groups with a com-

mon control, is also held out of action by a cam on the main drum. The auxiliary yarn finger 120 is held out of action by its operating thrust bar 132, and the auxiliary yarn is clamped on the dial by clamp 96.

The machine knits the well-known inturned welt 171, and at the completion thereof transfer is performed in customary manner. After the welt transfer, knitting of the shadow welt 172 continues at the main station only, with the welt yarn. At this point, the patterning mechanism is brought into action, the selectors being released by the final drum rack in transfer, and the selector drum idler plate is retracted by the same drum movement, whereby racking of the selector drum 8 commences. Also during transfer, the jack pressure cam utilized in make-up is brought into action to activate the pattern jacks, whereby they may be raised by the pattern jack cam 200 (FIGURE 4) in the usual manner. The pattern mechanism is set up to rack twice during each cylinder revolution, and as illustrated in FIGURES 29 to 31 the pattern layout is such that every eighth stitch in a course is a tuck stitch. That is, the pattern jack cam 200 and the pattern jacks are effective to raise and clear 7 out of 8 needles, leaving the eighth needle at tuck level. All courses of the shadow welt 172 are tuck courses. The tuck stitches in successive courses, however, are offset according to the irregular or random pattern indicated in FIGURES 29 and 30, so that the shadow welt displays an attractive mesh pattern in which no perceptible pattern lines or stripes appear. The foregoing matters are shown and described in A. E. Page Patent 1,969,853.

The final drum rack in transfer is also utilized to displace the bell crank 33, extending spring 30 and retracting clear cam 27 to inoperative position. Single feed knitting at the main knitting station continues through the shadow welt, the resulting fabric having the distinctive mesh pattern described above.

At the end of the shadow welt, a further rack of the main pattern drum is effective through a thrust rod to displace a yarn finger at the main knitting station, and introduce a body yarn which may be, for example, a 15 denier mono-filament nylon yarn. The same drum rack is effective to withdraw the welt yarn at the main station. This drum rack is utilized also to displace thrust bar 132 (FIGURE 19), and permit its spring 134 to move the associated yarn finger control 128 downwardly, which motion causes link 130 to displace the auxiliary yarn finger 120 to operative position. The yarn finger 120 introduces an auxiliary body yarn at the auxiliary station A, also preferably a 15 denier mono-filament nylon yarn. In the knitting of a stretch stocking, the body yarns introduced at the main and auxiliary stations may of course be oppositely twisted. For knitting of non-stretch stockings, untwisted yarns will be used.

The main drum rack which effects the foregoing yarn changes at the end of the shadow welt is utilized also to introduce the auxiliary stitch cam assembly 44 and the auxiliary sinker cam 80 in unique stepwise fashion, to initiate knitting at the auxiliary station A. This action may best be understood in connection with FIGURE 24, with particular reference to the stepped drum cam 163 illustrated therein. The rack referred to moves the cam 163 under the end 72 of bell crank 71, displacing the bell crank lever and permitting its end 72 to dwell momentarily on the leading cam step 163'. This initial movement of the bell crank lever 71 is transmitted by rod 70 to the bell crank 67 (FIGURES 11 and 12), and the resultant movement of the bell crank 67 displaces the auxiliary stitch cam assembly 44 inwardly to an intermediate position, whereat its cams are brought into substantial contact with the short butt needle group H (FIGURE 22). In this intermediate position, the auxiliary needle cams just miss the .240 butts of these needles.

As evident in FIGURE 12, the initial movement of the auxiliary stitch cam assembly is effective through its lug 85 and the rocker arm 84 to pivot the bracket 78, and

thereby move the auxiliary sinker cam 80 to a corresponding intermediate position, at which it is operative with respect to the long butt sinkers. As will be understood, this movement of the auxiliary sinker cam occurs during passage of the short butt sinkers which are associated with the 0.240 butt needles located between the group 148 and the first 0.270 butt needle 149.

The stepwise insertion of the auxiliary stitch cam assembly and the auxiliary sinker cam is utilized, in conjunction with related features about to be described, to close the eyelet which would ordinarily result on introduction of the auxiliary body yarn into the fabric. In the present invention, the eyelet is closed by knitting in the leading yarn end as at D in FIGURE 33, whereupon it extends across and effectively closes the eyelet. This is accomplished by the action of the special .270 butt needles 149 disposed near the trailing end of the short butt needle group H, together with the cams of the auxiliary stitch cam assembly, particularly the stepped auxiliary stitch cam 56 thereof. The auxiliary stitch cam assembly at intermediate position, against the short butt needles, is adapted to engage and actuate the .300 butts of the needle group 142, whereby knitting at the auxiliary station A will be initiated by the leading .300 butt needle 142. The special needles 149, however, lead the needle group 142, and their .270 butts are adapted to engage the auxiliary needle cams.

Referring to FIGURE 25, the .270 butts of the special needles 149 encounter the auxiliary clear cam 52, in intermediate position, and are elevated thereby to clear their latches and take the auxiliary yarn, which is suitably disposed for such purpose by the above described movement of the yarn finger 120. The intervening short butt (.240) needles pass across the clear cam at tuck level, and accordingly do not take the yarn. The special short butt needles 149 are then drawn down by the auxiliary stitch cam 56 to tuck level, coincident with the cam step 63 thereof, at which level they pass across the recessed lower portion 64 of the cam, immediately below the step 63. The recessed lower portion 64 of the cam is offset rearwardly, it will be apparent, so that it does not draw the .270 butts of the special needles 149 down to stitch level. In this manner, the special short butt needles 149 are separated from the other short butt needles solely by the action of the auxiliary needle cams, are raised to clear their latches and take the yarn in advance of the needle group 142, and are then lowered to tuck level but not to stitch level. The special short butt needles 149, having taken the yarn end, will knit at the main knitting station, whereby the yarn end is effectively knitted into the fabric to close the eyelet which would otherwise be formed. As in the case of the .240 butt needles preceding and between the special needles 149, the trailing .240 short butt needles 150 pass the auxiliary knitting cams at tuck level, without engagement.

As previously indicated, it is preferred to alternate the special short butt needles 149 with other .240 short butt needles, whereby only alternate needles take the yarn end in advance of knitting. In such case, when the special short butt needles 149 are drawn down to tuck level by the leading edge of the upper portion 65 of the auxiliary stitch cam 56, the yarn will pass to the rear of the intervening .240 short butt needles and become interlaced, whereby it is positively engaged and prevented from pulling out. This desirable interlacing of the yarn may be enhanced by slight inward misalignment or deflection of the hooks of the special needles 149, as indicated in exaggerated form in the right hand extension of FIGURE 22. Such misalignment of the special needles insures that the yarn will pass to the rear of each intervening .240 short butt needle, whereby the auxiliary yarn end may be perfectly interlaced as also illustrated in the right hand extension of FIGURE 22.

It is further preferred, as previously described, to provide a group of .240 short butt needles, such as the needle

group 150, between the special short butt needles 149 and the leading .300 butt needle 142. It has been found that if the trailing .270 butt special needle 148 is immediately or closely adjacent the leading .300 butt needle 142, the yarn will be drawn down by movement of the leading .300 butt needle to stitch level at a very sharp angle. This causes the yarn to be drawn across the latches of the special needles 149 which have taken the yarn, and the yarn end may occasionally be cut by the needle latches. By providing the short butt needle group 150 between the trailing special needle 149 and the leading needle 142, the yarn is drawn down by the leading needle 142 at a relatively shallow angle, as indicated in FIGURE 26, and cutting of the yarn by the latches of the special needles 149 is obviated.

It has been found desirable, also, to provide a slight slope in the auxiliary stitch cam step 63, whereby it descends from the leading edge to the trailing edge of the auxiliary stitch cam 56. The resultant slight draw down of the special needles 149 in passage across the auxiliary stitch cam is found to enhance the previously described interlacing of the yarns between the special needles 149 and the intervening .240 short butt needles, and to facilitate and make more certain taking of the yarn by successive special needles 149 and also by the leading needles of the .300 butt needle group 142. The latter, as previously stated, initiate knitting at the auxiliary station A, the corresponding sinkers being actuated by the auxiliary sinker cam 80 in intermediate position.

The eyelet closing described above occurs during the momentary dwell of the bell crank lever end 72 on the leading step 163' of cam 163 (FIGURE 24). The drum rack which initiates knitting at the auxiliary station terminates with the bell crank lever end 72 on the higher central step 163" of the cam 163. As will be evident, the further movement of the bell crank lever 71 occurring as its end 72 rises onto the cam step 163" is effective through rod 70 and bell crank 67 to displace the auxiliary cam assembly 44 inwardly to final operative position against the cylinder. This occurs after the last short butt needle has cleared the auxiliary stitch cam 56, or shortly after the needle position of FIGURE 26. The second stepwise movement of the auxiliary cam assembly is also effective through its lug 85 and the rocker arm 84 to displace the auxiliary sinker cam pullout bracket 78 to the final operative position illustrated in FIGURE 12. The auxiliary stitch cam group and the auxiliary sinker cam are accordingly positioned to actuate all needles and sinkers, whereby knitting at the auxiliary station A will be continuous.

Rotary knitting continues through the leg 173 of the stocking, knitting being performed at both the main and the auxiliary stations whereby the two body yarns are knitted in rotation. Patterning at the main knitting station continues, although it will be recognized that with both knitting stations active only alternate courses are held loop courses 177 knitted at the main station, being separated by intervening courses 179 in which the held loops are cast off as tuck stitches at the auxiliary station, as illustrated in FIGURE 28. In this manner, the body of the stocking is given a distinctive mesh pattern, generally resembling the mesh pattern of the shadow welt 172, but different therefrom by reason of the alternating course arrangement. Ankle tightening is accomplished in conventional manner.

For a purpose presently apparent, it is desirable in two-feed knitting of mesh stockings to terminate knitting at the auxiliary knitting station one course before going into the heel. This is accomplished by the mechanism illustrated in FIGURE 24. The main pattern drum 162 is racked four courses before the heel, and coincidentally the belt shipper drum 160 is racked to bring the notch 161 thereof into position to be engaged by the auxiliary clutch pawl 158. Three courses later, the cam follower 157 of the auxiliary clutch pawl is actuated by the stepped

cam 156 suitably positioned for such purpose on the high speed gear 155, whereby the belt shipper drum 160 and the main drum 162 are given a supplemental two step rack at this time (see A. E. Page, Patent 1,853,519).

The central step 163" of the main drum cam 163 is sufficiently long, it will be understood, so that the main drum rack which occurs four courses before the heel does not displace the bell crank lever end 72 from the step 163", but merely effects relative movement therebetween to position the lever end 72 on the trailing end of the central cam step 163". Initial movement of the cam follower 157 onto the leading step 156' of cam 156 is effective to displace the belt shipper drum 160 and the main drum 162 sufficiently to cause the lever end 72 to pass onto and temporarily dwell on the trailing step 163'" of the cam 163, this dwell corresponding to the dwell of cam follower 157 on the leading cam step 156'. Movement of the cam follower 157 onto the higher and trailing step 156" of the cam 156 is effective to further displace the belt shipper drum and the main drum of the machine to cause the lever end 72 to pass completely off the drum cam 163. In this manner, the auxiliary stitch cam assembly and the auxiliary sinker cam are withdrawn to inoperative position one course before the machine goes into the heel, in a stepwise fashion which represents the reverse of the stepwise insertion of these elements. Withdrawal of the auxiliary stitch cam assembly and the auxiliary sinker cam results from the action of spring 66 (FIGURE 11), the withdrawal being permitted by the movement of bell crank 67 in correspondence with the above described movement of bell crank lever 71.

The initial withdrawal of the auxiliary stitch cam assembly to intermediate position occurs during passage of the long butt needles T past the auxiliary knitting station. At intermediate position, as previously indicated, the auxiliary needle cams will pass the .240 short butt needles. Concurrently, the sinker cam 80 is withdrawn to intermediate position, at which position it will pass the short butt sinkers. As in the case of yarn insertion, this stepwise withdrawal of the auxiliary stitch cam assembly and the auxiliary sinker cam is utilized for the purpose of eyelet closing.

Referring again to FIGURE 22, it will be evident that with the auxiliary stitch cam assembly in intermediate position, the trailing .300 needle group 141 will be the last to knit at the auxiliary knitting station. The following group 148 of .270 short butt needles, however, is elevated by the auxiliary clear cam 52 to take the yarn and then drawn down to tuck level by the leading edge of the upper portion 65 of the auxiliary stitch cam 56, as previously explained in connection with FIGURE 25, at which level the butts of the needle group 148 pass across the lower portion 64 of the auxiliary stitch cam 56 under the step 63 thereof. The following .240 short butt needles, of course, are not elevated to take the yarn. The needles of group 148, accordingly, take the yarn at the auxiliary station but do not knit. These needles carry the yarn end around to the main station, whereat the yarn end is knitted into the fabric to cross and effectively close the eyelet which would otherwise occur on withdrawal of the auxiliary yarn. It has been found that interlacing of the yarn, as employed in eyelet closing on auxiliary yarn insertion, is not essential on auxiliary yarn withdrawal, as there is little tendency of the yarn end to pull out of the needle hooks. The result produced is that illustrated in FIGURE 32.

Taking of the yarn by the hooks of the needles of group 148 at the auxiliary knitting station occurs while the cam follower 157 is momentarily dwelling on the cam step 156', and while the lever end 72 is momentarily dwelling on the trailing cam step 163"". After this dwell, the cam follower 157 rides up onto the elevated step 156", giving the belt shipper drum and the main drum a final jog which moves the main drum cam 163 completely out

from under the lever end 72. The corresponding movement of the bell crank lever 71 effects further withdrawal of the auxiliary stitch cam assembly and the auxiliary sinker cam to final inoperative position. Such withdrawal of the auxiliary stitch cam assembly to final inoperative position occurs after the trailing .270 short butt needle 148 has been drawn down to tuck level by the auxiliary stitch cam 56, and preferably after the trailing needle 148 has passed the auxiliary stitch cam.

The final jog of the main pattern drum, corresponding to movement of the auxiliary clutch pawl cam follower 157 onto the trailing step 156" of the high speed gear cam 156, is utilized to actuate thrust rod 132 (FIGURE 19) and thereby effect withdrawal of the auxiliary yarn finger 120, and also to actuate the thrust rod 101 to momentarily displace bell crank 99 and rod 98 (FIGURE 18), to actuate clamp 96 and shear 97 to clamp and shear the auxiliary yarn. Withdrawal of the auxiliary yarn occurs, accordingly, immediately after the yarn is taken by the hooks of the needle group 148.

In the manner described, knitting at the auxiliary station is terminated one course before the heel, the auxiliary yarn is withdrawn, and the eyelet formed by withdrawal of the auxiliary yarn is closed. This insures that the final course knit before going into the heel is a tuck course knitted at the main station. One course later, that is one course after termination of auxiliary station knitting, a movement of the main pattern drum puts the machine into reciprocatory heel knitting in conventional manner. This drum movement effects a yarn change at the main knitting station, from, for example, the 15 denier body yarn to the 50 denier multi-filament heel and toe yarn. The same drum movement is utilized also to deactivate the patterning mechanism. As will be understood, this involves moving the selector levers out of operating position, release of the jack pressure cam, and outward movement of the guard plate for the selector drum 8 to effect automatic timing of the selector drum, all of which is conventional as disclosed in A. E. Page Patent 1,969,853.

The heel 174 is then knitted conventionally by reciprocatory knitting utilizing the short butt needle group H (FIGURE 22) and at the end of the heel the machine is brought out of heel knitting in the usual way. On coming out of the heel, body yarn is substituted for the heel and toe yarn at the main knitting station, and rotary knitting at the main station is initiated immediately. Simultaneously with initiation of rotary knitting at the main knitting station, the patterning mechanism is reactivated, in the manner already described. Just prior to the first reverse stroke of the needle cylinder at the beginning of the heel the instep needles of group I (FIGURE 22) are elevated to an inactive position and since their latches have been cleared they cannot form tucks upon their first passage through the cams M following the heel.

In the knitting of stretch stockings, the drum movement coming out of the heel, utilized to change yarn at the main knitting station, is utilized also to insert the auxiliary stitch cam assembly 44 and the auxiliary sinker cam 80, in the stepwise manner previously described, utilizing for this purpose the stepped cam 164 illustrated in FIGURE 24. In such case, knitting at the auxiliary knitting station is initiated promptly on coming out of the heel, the eyelet normally resulting from insertion of the auxiliary yarn being closed precisely as described in connection with the beginning of leg knitting.

As previously noted, by terminating knitting at the auxiliary station one course before the heel, the last leg course 191 (FIGURE 27) before the heel is a tuck course knitted at the main station. The first course 192 across the instep after the heel, as previously related, is necessarily a plain course knitted at the main station. This results in two consecutive courses 191 and 192 which preserve the alternating tuck pattern, but which however are both twisted in the same direction. Knitting at the

auxiliary knitting station having been initiated promptly on coming out of the heel, the second course 193 across the instep after the heel will be a plain course knitted at the auxiliary knitting station, whereby the first two consecutive courses 192 and 193 after the heel are both plain courses, but of opposite twist. The third course 194 across the instep after the heel will be a tuck course knitted at the main station. This procedure has been found to be particularly desirable, in that there are only two consecutive courses (191 and 192) across the instep of similar twist. The two consecutive courses of similar twist do not noticeably unbalance the fabric, and do not produce a perceptible stripe. Similarly, there are but two consecutive clear courses (192 and 193), which however are of opposite twist and similarly do not produce a perceptible stripe. In fact, it has been observed that the two consecutive courses of similar twist (191 and 192) tend to shorten up, thereby making less perceptible the consecutive plain courses 192 and 193. Termination 20 of knitting at the auxiliary knitting station one course before going into the heel, accordingly, is effective in the described mesh knitting of stretch stockings to produce an article in which the overall mesh pattern is most effectively preserved across the instep.

It may be noted at this point that in knitting two-feed mesh stockings with untwisted body yarns, the above described procedure may be varied by initiating foot knitting at the auxiliary knitting station a full course after the heel. Delayed initiation of foot knitting at the auxiliary knitting station may be accomplished by use of the standard auxiliary racking mechanism provided in the machine for coming out of the heel and toe. In such case, the machine is brought out of the heel in conventional manner, and immediately thereafter a suitably disposed cam on the high speed gear 155 in cooperation with an extra notch on the belt shipper drum 160 effects a supplemental jog of the main drum. This supplemental rack is utilized to change yarns at the main knitting station and to activate the patterning mechanism. This supplemental rack is also effective to bring the main drum into position to be racked by the make-up and transfer auxiliary mechanism, which then operates one course later to initiate knitting at the auxiliary knitting station in the stepwise fashion previously described, the main drum stepped cam 164 being suitably positioned for such purpose. The latter rack, of course, also inserts the auxiliary yarn at the auxiliary knitting station. Eyelet closing on the delayed initiation of knitting at the auxiliary knitting station is accomplished as previously described.

This procedure, utilized in two-feed mesh knitting with untwisted yarns, combined with the previously described expedient of terminating knitting at the auxiliary knitting station one course before going into the heel, results in a perfect mesh pattern across the instep of the non-stretch stocking. As in the case previously described, the last leg course 191 before going into the heel will be a tuck course knitted at the main station. Also as in the previous case, the first foot course 192 knitted across the instep after the heel will be a plain course knitted at the main station. If knitting at the auxiliary knitting station were initiated immediately on coming out of the heel, in this case, the second foot course 193 would also be a plain course, knitted at the auxiliary station. By activating the auxiliary knitting station one course later, however, the second foot course 193 following the heel is a tuck course knitted at the main station, and the third foot course 194 after the heel is a plain course, the first course knitted at the auxiliary station. Across the instep, then, courses 191 and 193 will be tuck courses, and courses 192 and 194 will be plain, the mesh pattern in this area being perfectly preserved through these courses and through the preceding and following courses.

After initiation of foot knitting at the auxiliary knitting station, either immediately on coming out of the heel

or a course later, rotary two-feed knitting proceeds throughout the foot 175. Going into the toe 176 a single drum rack is utilized to change yarns at the main station, and to effect stepwise withdrawal of the auxiliary stitch cam assembly and the auxiliary sinker cam, by means of the trailing half of the stepped cam 164 in the manner described in connection with the similar cam 163. This drum rack is utilized also to effect withdrawal of the auxiliary yarn finger 120. The trailing auxiliary body yarn is taken in the hooks of the needles 148, to effect eyelet closing in the manner described in connection with withdrawal of the auxiliary yarn on going into the heel. As will be understood, however, the auxiliary yarn is not in position at the moment to be clamped and sheared by the clamp 96 and shear 97. For this purpose, delayed action of the auxiliary yarn clamp 96 and the associated shear 97 is effected by the mechanism illustrated in FIGURE 18.

The main drum cam provided to actuate thrust rod 101 at this point is of adequate height to pivot the bell crank 99 sufficiently to displace the latch 104 downwardly and bring its step 107 under the bearing bracket 106. Spring 105 insures that the latch 104 moves inwardly when permitted, to the position whereat its step 107 underlies the bracket 106. This movement of bell crank 99 is also effective, of course, through rod 98, to open the clamp 96 and shear 97.

Subsequent retraction of the thrust rod 101, however, is not immediately followed by corresponding movement of bell crank 99, this being prevented by the engagement of latch 104 under the bearing bracket 106. Very shortly thereafter, however, the trip cam 109 provided on the rotating horizontal dial drive shaft 110 engages the latch cam surface 108 and displaces the latch outwardly against the action of the spring 105 to clear the latch step 107, whereby the clamp and shear spring loading is effective to displace rod 98 and bell crank 99, and close the auxiliary yarn clamp 96 and shear 97, the latch 104 returning to the normal position illustrated in FIGURE 18. This delayed action occurs concurrently with movement of the auxiliary yarn into proper position for clamping and shearing.

It may be noted that the delayed clamping and shearing action is not required and is not utilized on the commencement of heel knitting, which of course begins on a different part of the cylinder. For this reason, the main drum cam activating thrust rod 101 in going into the heel is lower than the corresponding cam activating the thrust rod 101 on going into the toe. The former cam is effective to momentarily open the auxiliary clamp and shear, and then permit closing thereof, but the thrust rod movement occasioned thereby is insufficient to displace the latch 104 to the point where its step 107 may engage below the bearing bracket 106.

The machine goes into the toe in conventional manner, other than as above described, and the usual gusset or ring toe is knitted at the main station with the 50 denier multi-filament heel and toe yarn, utilizing the needle group T in conventional reciprocatory manner. At the completion of the toe, the looper waste is knitted and the stocking then cast off in the well-known manner. This marks completion of the knitting cycle.

The clear cam 27, in the example described above, is active only in welt knitting. The standard retractable heel stitch cam is active during make-up, transfer, and knitting of the heel and toe only.

It will be evident that the machine described with only very minor modification may be utilized to knit single feed at the main knitting station only. The machine is adapted with equal efficiency to knit either stretch or non-stretch stockings with two feeds, and to knit either plain or mesh patterns. The mesh patterned stocking illustrated and described is distinguished by its unique appearance, closed eyelets, and continuity of the mesh pattern across the instep. The mesh pattern exhibits a

consistently excellent appearance, particularly in the case of stretch stockings, and the mesh pattern is also effective to prevent runs from running down the stockings.

It will thus be seen that there has been provided by this invention a machine, method and article in which the various objects hereinbefore set forth, together with many practical advantages are successfully achieved. As various possible embodiments may be made of the several features of the above invention, all without departing from the scope thereof, it is to be understood that all matter hereinbefore set forth or shown in the accompanying drawings is to be interpreted as illustrative, and not in a limiting sense.

I claim:

15 1. In a circular knitting machine, a rotary cylinder with independent needles, a retractable stitch cam for actuating said needles, means for moving said stitch cam in steps radially with respect to said cylinder, the lower portion of said stitch cam being recessed with respect to the upper portion thereof, and a unitary cam assembly including a base block, raising and lowering cams for knitting a gusset toe slidably mounted in said base block, means operatively linking said raising and lowering cams for differential action, and a clear cam slidably mounted in said base block for movement independently of said raising and lowering cams.

20 2. A circular knitting machine comprising a rotary cylinder with needles, said needles including a short butt group adjoined by leading and trailing long butt needle groups, an auxiliary yarn feed, a retractable auxiliary cam assembly including a clear cam and a stitch cam, means for moving said auxiliary cam assembly radially of said cylinder in steps, the lower portion of said auxiliary stitch cam being recessed with respect to the upper portion thereof, a few needles near each end of the short butt group having butts of intermediate length, and a delayed action auxiliary yarn clamp and shear mechanism including an auxiliary yarn clamp and shear, a bell crank, means linking said bell crank to said clamp and shear, a latch extending upwardly from said bell crank alongside the horizontal dial drive shaft and the bearing bracket of the machine, resilient means maintaining said latch in contact with said bracket, a step in said latch engageable under said bracket on downward movement of said latch, and a cam on said horizontal dial drive shaft, said cam being adapted and disposed to engage and displace said latch outwardly when the step thereof is engaged under said bracket.

25 3. In a circular knitting machine, an auxiliary yarn clamp and shear, a bell crank, means linking said bell crank to said clamp and shear, a latch extending upwardly from said bell crank alongside the horizontal dial drive shaft and the bearing bracket of the machine, resilient means maintaining said latch in contact with said bracket, a step in said latch engageable under said bracket on downward movement of said latch, and a cam on said horizontal dial drive shaft, said cam being adapted and disposed to engage and displace said latch outwardly when the step thereof is engaged under said bracket.

30 4. In a circular knitting machine, a rotary cylinder with independent needles, a retractable auxiliary cam assembly for actuating said needles, means for moving said cam assembly as a unit radially with respect to said cylinder, said assembly including a stitch cam, a landing cam below said stitch cam, a center cam leading said stitch cam and a clear cam leading said center cam, and means for adjusting said stitch and landing cams vertically with respect to said auxiliary cam assembly.
